Aug.

UNITED STATES PATENT OFFICE.

LOTHAR W. FABER, OF NEW YORK, N. Y.

DESIGN FOR AN ERASER-HOLDER.

SPECIFICATION forming part of Design No. 30,655, dated May 2, 1899.

Application filed April 10, 1899. Serial No. 712,546. Term of patent 7 years.

To all whom it may concern:

Be it known that I, LOTHAR W. FABER, a citizen of the United States, residing at the borough of Richmond, in the city and State of New York, have invented and produced a new and original Design for an Eraser-Holder, of which the following is a specification.

In the accompanying drawings, Figure 1 is a side view, and Fig. 2 is an end view in magnified size.

The leading feature of this design for an eraser-holder consists of a tube split at 2 and

having a rib 3 near the split end and a rib 4 around the other end and a band 5 with a nearly central rib 6.

15

I claim—

The design for an eraser-holder, substantially as described and shown.

Signed by me this 7th day of April, 1899.

LOTHAR W. FABER.
